(57) **CLAIM**

The ornamental design for a wearable portable light, substantially as shown and described.

DESCRIPTION

FIG. 1 is a perspective view of an ornamental design for a wearable portable light;

FIG. 2 is a rear perspective view of the design for a wearable portable light;

FIG. 3 is a front view of the design for a wearable portable light;

FIG. 4 is a side view of a first side of the design for a wearable portable light;

FIG. 5 is a side view of a second side of the design for a wearable portable light;

FIG. 6 is a rear view of the design for a wearable portable light;

FIG. 7 is a top view of the design for a wearable portable light; and,

FIG. 8 is a bottom view of the design for a wearable portable light.

Broken lines in the illustrations of the DRAWING indicate unclaimed parts of the article and/or unclaimed environment, such as a headband, that are not part of the design illustrated and claimed herein.

1 Claim, 5 Drawing Sheets
